Attorney

UNITED STATES PATENT OFFICE.

RAYMOND LESTER, OF JACKSONVILLE, FLORIDA.

PEDESTAL FOR RAILWAY ROLLING STOCK.

Application filed September 28, 1922. Serial No. 591,148.

To all whom it may concern:

Be it known that I, RAYMOND LESTER, a citizen of the United States, residing at Jacksonville, in the county of Duval and State of Florida, have invented certain new and useful Improvements in Pedestals for Railway Rolling Stock, of which the following is a specification.

The present invention consists of a pedestal for railway rolling stock.

Objects of the invention are to provide a pedestal equipped with wear take up members for increasing the longevity of the pedestal; to provide wear plates which may be applied, without unreasonable expense, to standard journal boxes and faced with wear elements which engage the journal boxes to augment the durability of the pedestal, insure evenness of wear on the latter and permit replacement of the wear plates with facility and expedition.

The above and other objects of this invention will be better understood from the following description of the present preferred form of the invention taken in connection with the accompanying drawings wherein:

Fig. 1 is a front elevational view of a pedestal constructed in accordance with this invention;

Fig. 2 is an end elevational view of the same;

Fig. 3 is a rear elevational view thereof;

Fig. 4 is a cross sectional view taken on the line 4—4 of Fig. 1;

Fig. 5 is a front elevational view of a slightly modified form of pedestal; and

Fig. 6 is a vertical sectional view of the form of pedestal shown in Fig. 5;

In the drawings a pedestal frame or body 7 is shown which is adapted for use with journal boxes of standard configuration and embodies parallelly arranged jaws 8 which may be of the skeleton type illustrated in Fig. 2. The outer faces of the jaws 8, both front and rear, have ribs 9 formed thereon each of which is provided with a recess 10 the terminal walls 11 of which are chamfered. By preference, the recesses 10 extend from a point in proximity to the upper wall 50 of the journal box receiving recess of the pedestal, downwardly to a point in proximity to the lower terminals of the jaws 8.

Each of the recesses 10 is adapted for the reception of a complementally formed wear plate 12. Each of the wear plates is prefer-

ably made of steel or any other material of equivalent integrity. The terminals of each plate are chamfered for snug engagement with the chamfered walls 11 of the recesses 10. When the wear plates 12 are mounted in the recesses 10 the inner faces of the plates are flush with the vertical inner walls of the jaws 8 as shown in Figs. 1 and 3. It will be observed, however, upon reference to Figs. 2 and 4 of the drawings, that the inner margins of the wear plates 12 extend inwardly beyond the inner margins of the jaws 8 to provide overhanging protective lips 13 for the exposed edges of the jaws. In this way, undue wear and disintegration of the jaws is eliminated. The wear plates are urged into the recesses 10 under pressure and are frictionally held from displacement in an apparent manner. This method of securing the wear plates eliminates the use of bolts or other securing means.

If desired a pair of wear plates may be provided for each jaw as shown in the form of invention illustrated in Figs. 5 and 6. These plates, as indicated at 14, have the lateral margins thereof chamfered, as indicated at 15, for engagement with the correspondingly chamfered walls 11' of the recesses 10' formed in the jaws 8'. The plates 14 are relatively thicker than the plates 12 so that each of said plates 14 provides a protruding breast which projects appreciably beyond the inner walls of the jaws 8'. The plates 14 are urged into the recesses 11' from the sides of the latter in an obvious manner. The terminals of the plate 14 project beyond the outer faces of the jaws 8' to provide overhanging lips 13' which protect exposed faces of the jaws.

It is of course to be understood that I am not limited to the specific construction of recesses formed in the jaws of the pedestal, the location of these recesses or the contours of the plates employed. However, the herein disclosed forms of invention will produce effective results and may be applied in a practical manner to standard pedestals. Other changes may be made in the invention within the scope of the appended claims.

What is claimed is:—

1. A pedestal for railway rolling stock including a frame embodying a journal box embracing jaws provided with recesses having chamfered walls, and wear plates engageable in said recesses and provided with

chamfered margins which complement said walls and frictionally engage the latter to prevent displacement of the plates.

2. A pedestal for railway rolling stock including a frame embodying journal box engaging jaws each of which is provided with a recess, and a wear plate engageable under pressure in each recess and equipped with an extension to protect exposed portions of said jaws substantially as described.

3. A pedestal for railway rolling stock comprising a body including journal box

embracing jaws provided with recesses having chamfered walls, complementally formed plates engageable in said recesses and 15 equipped with protruding breasts for engagement with the journal box.

4. A pedestal for railway rolling stock including journal box embracing jaws each of which has a dovetailed recess therein, and 20 wear plates complementing said recesses and engageable therein.

In testimony whereof I affix my seal.

RAYMOND LESTER. [L.S.]
